CENTRIFUGAL LIQUID CRUCIBLE.

Application filed October 23, 1926, Serial No. 143,682, and in France December 24, 1925.

Certain physical or chemical operations are very difficult to carry out and some of them are even impossible to realize, because vessels do not exist for the bodies treated, 5 capable of resisting either physical conditions to which they are subjected, or to the very action of said bodies. By way of example can be cited the melting of quartz. It has been up to now possible to carry out 10 this latter operation only in crucibles made of zircon which, whilst being very costly can only be used once, or in crucibles made of platinum-iridium which are excessively dear.

15 A process for the melting of quartz has also been proposed, according to which a rod of graphite is arranged in the axis of a vertical tube made of clay, the rod being heated, preferably, electrically, and the sand 20 is poured in the annular space provided between the graphite rod and the clay tube.

This process has the disadvantage of producing impure quartz, containing carbosilicon (CSi) and air and oxygen bubbles 25 which are included in the viscous mass and cannot evolve. Moreover, the quantity of quartz melted per unit of time is very small and does not allow the manufacture of articles of substantial dimensions.

30 The present invention has for object to overcome the above objections and produce practical vessels capable of resisting the above treatments or reaction, and substantially consists in replacing the solid crucibles by a liquid crucible constituted by a 35 body of a nature suitable for the actions which must take place by its contact and to which the required shape is given by the combined action of centrifugal force and gravity.

In fact, it is known that when a liquid contained in a solid casing is caused to rotate, the inner surface takes the shape of a paraboloid under the simultaneous action of centrifugal force and gravity.

45 When two liquids of different specific weights rotate together, the heavier, after attaining a certain speed comes to the exterior of the other liquid and acts as a casing or envelope for the same.

It is even possible to impart to the whole such a speed that the heavier liquid forms a ring or annulus and the lighter liquid comes in contact with the bottom of the vessel, this allowing it to flow away through 55 an orifice of this vessel.

The accumulation of the heavier liquid at the center of the apparatus cannot take place, owing to the fact that the amount of movement of this heavier liquid is several 60 times greater than the amount of movement of the lighter liquid, and also owing to the arrangement, on the walls of the crucible, of flutes for retaining the heavy liquid.

Owing to the application of these properties, it is possible, in accordance with the invention, to melt a body such as quartz within a liquid crucible, preferably made of molten metal, this metal can be copper, 70 manganese or chromium.

The said liquid crucible is formed within a casing comprising a rigid metal wall and a refractory coating.

The invention is also characterized by the special arrangements of the apparatus.

It is provided with heating means for bringing the bath of metal to the required condition of fluidity and supplying the heat necessary for the reaction. Preferably, the heating is effected electrically by means of 80 eddy currents.

These currents are generated by one or more conductors wound in a spiral and forming one or more layers about the apparatus; the said conductor comprises a pipe which 85 serves at the same time for supplying air, water or oil for cooling purposes.

For allowing these currents to act efficiently on the metal, the latter can enter an annular space comprised between a solid 90 cylindrical wall, in which is embedded the electric conductor.

The air, water or oil for cooling purposes is fed by a system of distribution comprising crowns, rotating with the rotary part of 95 the apparatus, and fixed crowns; the joint between these crowns is so arranged that the parts in contact tend to be pressed against each other by the pressure.

The system of distribution of air, water 100

or oil serves also for the distribution of the electric current and the arrangements of the friction parts and elements through which pass the current are such that large cross sections are offered to the passage of the current.

The apparatus is completed by means permitting to increase the speed of rotation of the heavier body at the time it is desired to drive out the lighter body from the apparatus, so as to allow the lighter liquid to come in contact with bottom of the apparatus.

In order that the invention may be clearly understood, a form of construction of the said apparatus is illustrated, but by way of example only, in the accompanying drawing in which:

Fig. 1 is a vertical section of the new apparatus.

Fig. 2 is a horizontal section.

Figs. 3 and 4 are detail sections.

As illustrated in the drawing, the apparatus consists in a metal box or casing *a*, internally coated with a refractory lining *b* made of magnesia, quick lime, etc.

The whole constitutes the solid crucible within which is formed the liquid crucible; for that purpose this solid crucible is rotatably mounted on ball rings *c d* and it can be driven by means of one or more pinions *e* gearing with a toothed ring *a¹* rigid with the box *a*.

This rotary structure, or rotor, is completely enclosed in an external casing comprising a cylinder *f*, made of a material which is a bad conductor of heat, through which pass one or more pipes *g* into which is sent air, water or oil, for cooling the said external-casing. The cylinder is provided with a top or cover *f¹* and a bottom *f²*.

The space *c¹* is filled with oil, so that all the ball bearings and gears run in oil. The latter is cooled by its contact with the cooling pipes *g*.

The interior of the crucible *b* presents a concave bottom, the central part of which is raised, as shown in the drawing, forming a projecting duct made of or covered with zircon and adapted to facilitate the evacuation of the body treated. At the upper part, a boss *h* prevents the molten metal from rising too high. At a certain distance from the side wall is arranged a cylinder *i*, made of refractory material, leaving between it and the lining *b* two annular intervals or spaces *j* into which can enter the molten metal *u* constituting the liquid crucible. This cylinder *i* is connected to the solid crucible by bonds as few in number and as narrow as possible so as to leave an easy access for the metal *u*.

Through the cylinder *i* pass one or more metal pipes *k*, wound in a helix, forming a

winding, in one or more layers, which serve to feed the single phase, two phase or three phase alternating current generating the eddy currents, and which allow also to bring air or another fluid for cooling purposes. It results from the arrangement of the conductor *k* that the metal contained in the annular spaces *j* is in the field of the currents and highly heated. Owing to the fact that the metal is thus brought about the conductor *k*, the electromagnetic losses are avoided.

The ends of the tube *k* lead to annular cavities *l, m* formed by a combination of rotating crowns or rings rigid with the rotor, and of fixed crowns or rings. The air, or any other fluid, is brought into one of the cavities by a conduit *l¹* and led away by another conduit *m¹*. In case of polyphased currents, the crowns or rings will be used in any suitable number.

Fig. 3 shows the detail of one of the annular cavities; *a* designates a portion of the metallic bottom on which are secured, by means of bolts *o* passing through insulating members *o¹*, rings *p* shown in side view in the drawing; these rings are in contact through surface *q* (the profile of which is in the shape of an inverted V) with a ring *p¹* (the profile of which is of U-shape) which is fixed and in which opens one of the pipes *l¹* supplying air or any other fluid. The contact surfaces *q* are lubricated under pressure by the oil of the bath *c¹* (Fig. 1) and particularly by the oil under pressure supplied to the surface *q* through the openings provided in the ring *p¹*.

The other annular cavity is similar.

The admission of the current is effected through the member *p¹* on which rub two arms *r* a spring *r¹* tending to space apart the said arms *r*, thus placing them in electric connection, as shown in Figs. 3 and 4.

For preventing the passage of current to the bottom *o*, the conducting members are separated from the bottom *o* by insulating parts *o¹*, made of mica for instance.

The apparatus further comprises a plug *s*, normally closing the bottom of the apparatus and capable of being moved away therefrom at the required moment. A pneumatic control has been illustrated by way of example for producing the movement of this plug. For that purpose, the said plug is rigid with a piston *s¹* moving in a cylinder *s²* and compressed air can be sent above or below the piston for lowering or raising the plug.

The apparatus is completed by a hopper *t* for the introduction of sand or other material *z* to be melted; it can be fed by an Archimedes screw receiving the material from an elevator hermetically enclosed in a casing. A tube *v* supplies hydrogen or another

gas, when the operation must be carried out in this gas.

The operation is as follows:

The current is fed to the apparatus and passes through the members p^1 and r (Fig. 3) and through the conductor k ; the eddy currents generated produce a high temperature which ensures the melting of the metal u . The rotor is caused to rotate; under the combined action of centrifugal force and gravity, the molten metal takes the shape of a paraboloid, as indicated in the drawing, so that it constitutes the liquid crucible in which the desired reaction can take place.

15 Air is exhausted from the apparatus, if this has not already been effected, by dis-

placing it by a current of nitrogen or other suitable gas, supplied by the conduit v .

20 The material to be treated (quartz or pure sand to be melted) is introduced into the apparatus. This material being subjected to a very high temperature, is melted.

25 During the entire operation, the air or other fluid supplied by the pipe l^1 passes in the tube k and prevents the wall i from reaching a too high temperature which would diminish the electroconductibility of the tube k . The wall a is cooled by the oil bath c^1 and the latter is cooled in its turn 30 by the circulation of cold water in the tube g .

35 When the quartz is sufficiently fluid and liquid and it is desired to cast it, the speed is increased so that the liquid u takes the shape of an annulus or ring and that the liquid z may thus reach the solid bottom and the tap hole.

40 The product obtained can contain traces of oxide of lead or of silicium, but not to the extent of rendering it unsuitable for the uses for which it is intended: laboratory or cooking apparatus, replacement of cast-iron stones, of window glass, construction of water conduit pipes, etc.

45 The invention is applicable whenever it is impossible to use solid crucibles, either for technical reasons for instance owing to the chemical affinity between the substance of the crucible and that of the liquid, or for financial reasons, when the price of the material of the solid crucibles is too high.

50 The invention can be realized according to any modification based on the above-mentioned principles and all the details of execution can be varied according to circumstances without departing thereby from the principle of the said invention.

Claims:

55 1. An apparatus for forming liquid crucibles, comprising a vessel provided with a refractory lining, said vessel being adapted to contain molten metal to form the crucible, an electrical conductor embedded in said lining, and means for rotating the vessel.

2. An apparatus for forming liquid crucibles, comprising a vessel provided with a refractory lining having a concave bottom and an annular inwardly projecting member, an electrical conductor embedded in the said member, and means for rotating the vessel. 65

3. An apparatus for forming liquid crucibles, comprising a vessel provided with a refractory lining having a concave bottom and provided with an annular and inwardly projecting member, passages opening into the vessel being formed between the body of the lining and the inwardly projecting member, an electrical conductor in said member, and means for rotating the vessel. 75

4. An apparatus for forming liquid crucibles, comprising a vessel having a concave bottom and adapted to contain molten metal to form the crucible, heating means in the wall of the vessel, a jacket spaced from the vessel, a cooling medium in the jacket, and means for rotating the vessel. 80

5. An apparatus for forming liquid crucibles, comprising a vessel having a concave bottom and adapted to contain molten metal to form the crucible, heating means in the wall of the vessel, a jacket spaced from the sides and bottom of the vessel, the said space being adapted to contain oil, and means for rotating the vessel, said means being mounted in the space below the bottom of the vessel, whereby said means will be lubricated by the oil in the said space. 90

6. An apparatus for forming liquid crucibles, comprising a vessel provided with a refractory lining having a concave bottom, an electrical conductor embedded in the refractory lining, a jacket spaced from the vessel and having a cooling medium therein, and means for rotating the vessel. 100

7. An apparatus for forming liquid crucibles, comprising a vessel provided with a refractory lining having a concave bottom and an annular inwardly projecting member, passages opening into the vessel being formed between the body of the lining and the inwardly projecting member, an electrical conductor in the said member, a cooling jacket spaced from the vessel, and means for rotating the vessel. 110

8. In an apparatus for forming liquid crucibles, a rotatable vessel provided with a refractory lining having a concave bottom adapted to contain molten metal to form the crucibles, electrical conductors embedded in the lining, and contacting rotary and fixed ring-like members, the conductors being connected with the rotary member, and the fixed member connected with an electrical supply. 115

9. In an apparatus for forming liquid crucibles, a rotary vessel provided with a refractory lining having a concave bottom and an annular inwardly projecting member, pas-

sages being formed between the member and the body of the lining and opening at their ends into the vessel, electrical conductors embedded in the inwardly projecting member of the lining, rotary and fixed ring-like members below the vessel, and means for holding said members in electrical connection, the rotary members being connected

with the conductors and the fixed members connected with an electrical supply.

The foregoing specification of our "centrifugal liquid crucible" signed by us this 8th day of October, 1926.
